UNITED STATES PATENT OFFICE.

JOHN W. CULP, OF SOUTH BEND, INDIANA.

CARD GAME.

1,111,882.

Specification of Letters Patent. Patented Sept. 29, 1914.

Application filed April 2, 1914. Serial No. 829,012.

To all whom it may concern:

Be it known that I, JOHN W. CULP, a citizen of the United States, residing at South Bend, in the county of St. Joseph and State of Indiana, have invented certain new and useful Improvements in Card Games, of which the following is a specification.

The invention relates to an improvement in games, and particularly to a series of 10 game playing elements, such as cards, blocks, or the like, arranged in distinctive series by characteristic face markings, with all of such elements having back markings identical one with another except in a single detail, as for example, in size, the selection of the cards in the playing of the game being controlled by the back markings.

The improved game contemplates a pack or number of cards, blocks or the like, arranged in series, the cards of each series having distinctive face markings, as for example, successive numerals or letters, with such face markings of one series distinguished from the similar face markings of 25 each of the remaining series by variation in color, the back markings of all of such cards, blocks or the like, being identical, one with another, except in a slight particular, whereby each element differs from every element.

30 The invention in the preferred form of details will be described in the following specification, reference being had particularly to the accompanying drawings, in which:—

35 Figure 1 represents a face view of a series of playing elements used in the improved game. Fig. 2 is a back view of the same elements.

In accordance with the illustration here- 40 with, it will be seen that I provide a number of playing elements, such as cards, blocks or the like, as 1, which elements are divided into distinctive series, for example 2, 3, 4, and 5. The elements of each series bear on 45 their face distinctive data, in the instance shown being numbered successively from 1 to 5, the data of one series being distinguished from the similar data of each of the other series by distinctive coloring. In 50 the instance shown, the data 6 of series 2 will be in red, the data of series 3 in white, the data of series 4 in blue, and the data of series 5 in yellow.

The backs of the respective elements are 55 each of exactly similar marking except in

one particular, and in the instance shown the backs of all of the elements will have a color strip 7 arranged transversely thereof with the upper and lower marginal edges slightly divergent. The degree of divergence is uniform throughout the entire number of playing elements used, so that with the cards or other elements arranged edge to edge as shown, the back marking indicates a proportional increase for each successive 60 card or element of each series. That is, the back marking increases in size through each series in accordance with the value of the face marking of the elements of that series, the lowest or first card of each series having the smallest back marking of that series, 65 and so on throughout the series.

In playing the game, the cards, blocks or other elements are placed face down and mixed thoroughly. The players, each being 70 limited to the cards of one series, aims to select a card from the mass in his series, relying solely upon his ability to distinguish his series by the comparatively slight variation in the back marking of the cards of 75 his series from the remaining cards. If the card selected belongs in the series controlled by the particular player, the card is retained by such player, but if the card selected belongs in another series, it is left face upward 80 to be selected at will by the player to whose series it belongs. There is thus provided a penalty for the selection of the wrong card. The player first completing the cards in his 85 series is the winner.

It is of course to be understood that the above description and illustration is indicative of the general arrangement of the face and back markings of the improved playing elements, and that the distinctive 90 feature of the invention is the arrangement of the face markings in distinctive series and the arrangement of the back marking in practically identical formation, variable in a slight particular only. I contemplate 95 any and all variations of the arrangement, as for example, making the elements in the form of blocks having the face markings of the alphabet, with the blocks themselves of 100 slightly different and proportionally increased sizes. Any desired face marking may be used and any desired back marking so long as the respective elements in such back marking differ slightly one from another in their successive order.

What is claimed is:-

1. A series of game playing elements having back markings of similar and proportional variation throughout the set of such 5 elements.
2. A series of game playing elements having similar back markings, said markings being distinguishable by size variation only.
3. A series of game playing cards having 10 similar back markings, said markings increasing in size and in direct proportion throughout the series of cards.

4. A series of game playing cards having similar back markings, and grouped distinctive face markings, the back markings varying in size successively throughout the series and throughout each group of distinctive face markings.

In testimony whereof I affix my signature in presence of two witnesses.

JOHN W. CULP.
